(57) **CLAIM**

The ornamental design for a part of a digital mixer, as shown and described.

DESCRIPTION

FIG. 1 is a perspective view of the front, top and right side of a part of a digital mixer showing my new design;

FIG. 2 is a front view thereof;

FIG. 3 is an enlarged view at 3-3 lines in FIG. 1; and,
FIG. 4 is an enlarged view at 4-4 lines in FIG. 2.

The broken lines shown are included for the purpose of illustrating the environment of the design only and form no part of the claimed design.
